US00D626551S

(12) **United States Design Patent**
Julien

(10) **Patent No.:** **US D626,551 S**
(45) **Date of Patent:** **** Nov. 2, 2010**

(54) **COMBINED PDA DEVICE AND BASE STATION**

(75) Inventor: **Olivier Julien**, Mérignac (FR)

(73) Assignee: **Implanet**, Martillac (FR)

(**) Term: **14 Years**

(21) Appl. No.: **29/350,853**

(22) Filed: **Nov. 24, 2009**

(30) **Foreign Application Priority Data**

May 26, 2009 (FR) 09 2509

(51) **LOC (9) Cl.** **14-02**

(52) **U.S. Cl.** **D14/341**

(58) **Field of Classification Search** ..... D14/341-347, D14/137, 138, 138.1, 138 AA, 138 R, 138 AB, D14/138 G, 138 A, 496, 426, 429, 129, 130, D14/420, 439-441, 448, 125, 147, 156, 218, D14/250, 389, 336, 203.1, 203.3, 203.4, 203.7, D14/315, 388-390, 434, 447, 432, 385, 357, D14/149, 457, 253, 251, 356, 107, 155; D21/324, D21/329, 330, 333, 392; D10/65, 104; D18/6-7; 345/169, 901, 905, 156, 157, 168, 173; 361/814, 361/680, 686, 679.27, 679.3; 341/22; 348/168; 379/433.04, 433.07, 433.11, 916, 433.01, 379/433.06; D13/199, 107, 108, 118, 109, D13/110, 119, 184; D19/65; D8/395; 24/303; 455/557, 556.1, 556.2, 573; 439/374, 131, 439/529, 534, 929, 346, 31, 640; 235/472.01; 248/309.1, 221.11; 429/100

(57) **CLAIM**

The ornamental design for a combined PDA device and base station, as shown and described.

DESCRIPTION

FIG. 1 is a perspective view of a combined PDA device and base station showing the new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

1 Claim, 6 Drawing Sheets

FIG. 1

FIG. 2

FIG. 3

FIG. 4

FIG. 5

FIG. 6

FIG. 7
